UNITED STATES PATENT OFFICE.

JOHN HEBERLING, OF ROCHESTER, NEW YORK.

PRINTING MACHINE.

1,423,325.

Specification of Letters Patent. Patented July 18, 1922.

Application filed April 26, 1921. Serial No. 464,522.

To all whom it may concern:

Be it known that I, JOHN HEBERLING, a citizen of the United States, and resident of Rochester, in the county of Monroe and 5 State of New York, have invented certain new and useful Improvements in Printing Machines, of which the following is a specification.

The present invention relates to printing machines and an object thereof is to provide, in a printing machine of the type having a rotary carrier with movable printing elements thereon, means for effecting a radial movement of the printing elements to printing 10 positions on the carrier, such means rigidly and firmly supporting the printing elements in printing positions. A further object of the invention is to provide in a printing machine of the type having a rotary carrier with movable printing elements thereon, means for effecting a movement of the printing elements both radially and longitudinally of the axis of the printing carrier to and from printing position. An 15 other object of the invention is to provide a printing element with a rupturing means independent of the printing surface. A further object of the invention is to provide in a printing machine of the type having printing 20 elements movable thereon to and from printing position, a resetting means for resetting the printing elements, said resetting means being movable to an inoperative position so that the printing elements will not 25 be affected thereby. A still further object of the invention is to provide in a printing machine having a rotary carrier with movable printing elements thereon, a novel means for locking the printing elements in 30 printing position. Still another object of the invention is to provide in a printing machine of the type having a rotary carrier and movable printing elements thereon, an aligning device which will insure the proper positioning 35 of the printing elements in printing positions on the rotary carrier. A further object of the invention is to provide in connection with a printing machine of the type having a rotary carrier with printing surfaces 40 thereon for cooperation with a rotary platen, rupturing means which will rupture the work to one side of the printing line for the purpose of rendering difficult the changing of the payee's name in a negotiable instrument. Still another object of the invention is to provide in a printing machine 45

which prints and feeds the work, a means which will impart a slight return movement of the work so that proper spacing in the printed matter is obtained. Another and 50 still further object is to provide a rupturing means independent of the printing surfaces for returning the work slightly after a printing and feeding operation.

To these and other ends the invention consists of certain parts and combinations of parts, all of which will be hereinafter described, the novel features being pointed out in the appended claims.

In the drawings:

Fig. 1 is a side view of a machine constructed in accordance with this invention;

Fig. 2 is a front view of the machine;

Fig. 3 is a plan view;

Fig. 4 is a bottom view;

Fig. 5 is a vertical central section through the machine;

Fig. 6 is a view of the under side of the upper part of the machine;

Fig. 7 is a vertical section on the line 7—7, 80 Fig. 5;

Fig. 8 is a vertical section on the line 8—8, Fig. 6;

Fig. 9 is a rear fragmentary view of the rotary carrier;

Fig. 10 is a sectional view on the line 10—10, Fig. 4, showing the slip connection between the spring and the shaft of the rupturing roller;

Fig. 11 is a section on the line 11—11, 90 Fig. 5;

Fig. 12 is a fragmentary view showing the manner in which the printing devices are returned to their normal positions;

Fig. 13 is a fragmentary view showing a 95 printing device in printing position on the rotary carrier;

Fig. 14 is a perspective view of one of the printing devices; and

Figs. 15 and 16 are detail views of the work returning mechanism, the former showing the spring with energy stored therein and the latter showing the spring in normal position.

In the embodiment of the invention herein 105 illustrated, there is provided a frame comprising a lower or base section 1 and an upper or top section 2 secured to the lower or base section by screws 3. The lower or base section is spaced at its front at 4 from the upper section to provide a slot through which the work may be passed and the top 110

of the base section on one side of this slot is provided with a plate 5 which serves as a support for the work. The under side of the upper section 2 above the slot has a cover 5 plate 6 which protects the upper face of the work against the action of ink or grease from the parts in the upper section, this plate 6 being held in place by screws 7.

A platen 8 is mounted in the lower section, while the printing mechanism is mounted in the upper section. In this embodiment of the invention, the platen is in the form of a roller secured to a shaft 9 and having its periphery operating through a slot 10 in the work support 5 so that the printing mechanism may cooperate with the platen. The shaft 9 may be supported in any suitable manner. In this instance, it is journaled at opposite ends in two arms 15 11 which are pivotally supported at 12 on the base 1 and have screws 13 at their outer ends anchored in lugs 14 on the base 1. These arms also carry screws 15 which have abutments against said lugs 14. By this arrangement it is possible to adjust the arms 12 with the shaft 9 carried thereby so that the roller 8 may be moved toward and from the printing mechanism for the purpose of increasing or decreasing the pressure on 20 the work.

The printing mechanism, in this embodiment, is in the form of a rotary carrier 16 secured to a shaft 17 by a screw 18, the shaft being journaled at 19 in the upper section 2 of the casing, its rear end extending through the casing and having a handle 20 connected thereto through which the shaft and the rotary carrier of the printing mechanism may be turned. The rotary carrier 25 has the printing elements movably mounted thereon and adapted to be projected to printing positions for engagement with the platen 6. These printing elements are, in this instance, in the form of blocks 21 arranged in radial grooves 22 formed in the rotary carrier 16. To the end that these blocks may be individually projected from the carrier, the carrier has the bottom surface 23 of each groove inclined with relation to the axis of turning of the carrier to form a guide and the bottom surface of each printing element is also inclined to cooperate with the inclined bottom of the groove, thus providing two cam surfaces, 30 which, when the printing member is moved longitudinally of the axis of the rotary carrier, causes the printing member to move also radially of the carrier so that the printing character 24 lies in a position to cooperate with the platen 8 when the rotary carrier is turned to bring the character to the platen. At this time the character will operate through a slot 25 formed in the plate 6. With the object in view of effecting the 35 movement of the printing element longitudi-

nally of the rotary carrier and also radially thereof, each printing element is provided with a key 26, this key having its stem 27 connected to the printing element and the keys projecting from the front of the upper 70 casing section 2 and lying in an annular series, suitable indicating matter being provided on the keys to correspond with the printing characters 24. With the purpose in view of confining the printing elements 75 27 in the grooves, a cap plate 28 may be provided on the front of the rotary carrier 6, this cap plate having a flared flange 29 which projects into notches 30 in the printing elements to cooperate with one wall of 80 said notch. The outer ends of the printing elements beyond the cap plate are covered by a ring 30^a which has radial slots 31 through which the stems 27 of the casing 26 extend.

With the object in view of locking the printing elements in printing position on the rotary carrier 16, locking means is provided, in this instance, in the form of a plate 31^a secured by screws 32 to the rear 90 face of the rotary carrier 16, the periphery of this plate being engaged by inclined or cam portions 33, one on each printing element, each cam portion cooperating with the plate 32 when the printing element is 95 moved by its key 26 and causing the printing element to move slightly away from the bottom wall of the groove in the rotary carrier until the end of the cam portion 33 is reached. At this time the shoulder 34 100 formed at the end of the cam portion 33 will engage the rear face of the plate 31^a and lock the printing element in its printing position. In order that the printing element may be held in engagement with the 105 plate, each printing element has a helical spring 35 connected at one end to a projection 36 on the rear end of the printing element and its inner end to a screw 37 on the rear face of the printing element, this spring 110 also serving to return the printing element to non-printing position when the printing element is released by the locking means. To facilitate the movement of the printing member in the groove under the action of 115 the cam 33, the forward end of the printing member may be bevelled at 38.

With the end in view of insuring the engagement of the shoulder 34 with the plate 31^a in order that proper alignment of the 120 printing surfaces may be obtained, there may be provided an aligning device comprising, in this instance, a plate 49 secured at 50 and extending downwardly from its point of attachment to the path of travel of the projections 36, this plate being so deflected or bent that the projections may freely ride onto its surface to be engaged by the latter in order to move the printing element longitudinally or in the direction of the axis of 130

the rotary carrier. The particular form of this aligning device gives to it resiliency which prevents injury of any of the parts of the machine.

- 5 For the purpose of releasing the printing elements to permit them to return to normal position out of printing position under the action of springs 35, there may be provided an actuating device 39 in the form of a rotary disk arranged on a shaft 40 which is movable longitudinally in order to move the disk 39 into and out of a position where the cam will cooperate with the projections 36 and effect the movement of the printing elements out of connection with the locking plate 31^a, this position being shown in Fig. 12 and the inoperative position being shown in Fig. 13. The shaft 40 may be controlled by an arm 41 extended laterally from the shaft 20 through the side wall of the casing and having a finger piece 42 at its outer end. The arm works in an L shaped slot 43 in the casing and, when at one end of the slot, the operating or actuating device 39 will be in operative position, while, at the opposite end of the slot, it will be in inoperative position. A coil spring 44 surrounds the shaft 40 and tends normally to project the operating member 39 into the path of the projections 36 on the printing member. When the operating arm 41 is in the vertical portion of the slot 43, the spring 44 will be under compression.

Provision is made when the invention is embodied in the check printing machine, for breaking that portion of the paper on which the payee's name is written so that the changing of the name is rendered impossible or difficult. This result is secured, in this instance, by providing on each printing member 21, a paper rupturing or breaking surface 45, this surface being substantially in a plane with the printing surface 24. This surface will, because of its being mounted on the printing member, be projected to operative position when the printing surface 24 is projected to printing position on the rotary carrier. For cooperating with the rupturing devices or surfaces 45, there may be provided a rupturing device 46 for engaging with the work on that side thereof opposite the surfaces 45. This rupturing device 46 is, in this instance, in the form of a roll having a roughened or serrated face, and mounted to turn about an axis common to the axis of turning of the platen 8 and preferably being secured to the shaft 9 on which the platen is arranged. It is apparent that adjustment of the platen to effect different pressures on the work will also effect different pressures between the rupturing devices 45 and the rupturing device 46. The work support 5 is provided with a slot 47 through which the rupturing device 46 operates, while the bottom plate 6 is provided with a slot 48 through which the rupturing devices 45 operate.

It has been found that the cooperation between the printing characters and the rupturing devices on the printing elements with the platen and the rotary rupturing device 46 effects a movement of the work or check beyond the amount necessary to provide a proper space between the printed matter and with the object in view of securing a proper spacing between the printing characters, means is provided for returning the work slightly, this means, in this instance, being independent of the printing surfaces and preferably being effected through the connection of said work returning means with the platen and the rupturing roller 46. In this embodiment, this means comprises a spring device which has a slip joint connection with the shaft on which the platen 80 and the lower rupturing devices are mounted so that after cooperation between the platen and the printing member has ceased, the rupturing device through its engagement with the work will effect the slight return 85 of said work in a direction opposite to that effected through the printing action. The dot and dash line A, Fig. 16, indicates the amount the work is returned, Fig. 15 showing the position the work occupies at the completion of the printing movement, and Fig. 16 shows the position of the work after shifting. Specifically this work returning device embodies a spring 52 which is anchored at 53 at one end and is curled or 100 rolled at 54, its other end being secured at 55 to the slip device which cooperates with the shaft 9 on which the platen and rupturing roller 46 are mounted. This slip device, in this instance, embodies two clamping 105 plates 56 and 57 curved to embrace a sleeve or cylindrical member 58 on the shaft 9 and having portions extending in parallel spaced relation, one end of one of these parallel portions being turned inwardly at 59, while the end of the other member is extended beyond the turned end 59 and is slotted at 60 so that it may be guided in the stem 61 by which the head 53 which secures the spring 52 is secured. A screw 62 connects 110 the parallel portions and serves to adjust the pressure of the curved portions on the sleeve 58. In operation, when the printing member with the rupturing device 24 thereon engages the platen and the rupturing device 46, the shaft 9 will be turned and this causes the members 56 and 57 of the slip-off device to shift from the position shown in Fig. 16 to the position shown in Fig. 15, thus storing energy in the spring 52. After 115 the slip-off device has moved to the limit of its movement, the sleeve 58 may continue to turn with the shaft 9 until the completion of the printing operation. When the rupturing surface 45 moves out of engagement with 120 the printing member, the spring 52 will 125 return the sleeve 58 to the position shown in Fig. 16, thus returning the work to the position shown in Fig. 15. After the work has been returned to the position shown in Fig. 15, the printing member 24 will again engage the platen 8 and the rupturing device 46, thus returning the work to the position shown in Fig. 16. This cycle of operations will be repeated until the printing operation is completed.

the rupturing roller 46, the shaft 9 will be freed and will be turned through the energy stored in the spring 54 acting on the slip-off device formed by the members 56 and 57.

5 Any desirable means may be employed for holding the work against accidental displacement while the printing elements are out of cooperation therewith. In this instance, a work holding device 62 cooperates 10 with the work support 5 and is carried by an arm 63 which extends through a slot 64 in the casing 2 from a rock shaft 65 journalled in said casing, this rock shaft having an operating arm 66 extending laterally 15 therefrom to the exterior of the casing through a slot 67, the outer end of the arm having a finger piece 68 which, when depressed, turns the rock shaft to elevate the work clamp 62, a coil spring 69 surrounding 20 the rock shaft and tending to return the work clamp 62 in cooperation with the work support 5.

The printing characters may be inked through any suitable means. In this instance, the wall of the casing 2 is provided with an opening 70 on opposite sides of which flanges 71 project. Fitting over these flanges is a cover plate 72 whose lower edge 73 locks with a groove or recess 74 in the casing 2 and whose upper edge is held by a latch 75 pivoted on a pin 76. This cover plate carries a post 77 to which the arms 78 of an ink roller carrying frame are pivoted at 79. Rollers 80 are 35 journalled in this frame, one of said rollers cooperating with the printing faces, while the other of said rollers acting to supply ink to said roller 80. A stop 81 limits the movement of the rollers toward the carrier 40 16 under the action of a spring 82.

The operation of the invention will be understood from the foregoing description, but it may be summarized as follows:

The work X is placed upon the work support 5 under the work clamp 62. One or 45 more of the keys 26 are engaged by a finger of the user to press the printing elements inwardly so as to cause them to move both longitudinally and radially with reference 50 to the shaft 17 through the cooperation of the inclined surfaces on the printing elements with the surfaces 23 until the shoulders 34 engage with the plate 31, as shown in Fig. 13. In this position, the printing 55 surface 24 and the rupturing surface 45 will be in positions to engage respectively the platen 8 and the rupturing surface 46 when the rotary carrier 16 is turned. Ordinarily only one of the printing elements 21 is 60 moved for each turning movement of the rotary carrier, but if the matter to be written occurs in the same succession in the rotary carrier, then more than one of the printing elements may be moved to printing 65 position, as for instance, when \$48.00 is to

be written, the printing elements carrying the sign \$, 4 and 8 are moved to printing position before the rotary carrier is turned. Thereafter the rotary carrier is turned and the characters will be successively printed 70 on the work through the one rotation of the carrier. Of course, if these characters are reversed as \$84.00, then this operation cannot be followed and only the \$ sign with the 75 8 can be printed together, a separate operation being required to print the 4. By this arrangement if the characters occur on the printed matter in the same order on the machine, it is possible to set the machine, by moving the resetting device 39 to an inoperative position as shown in Fig. 13, so as to print a number of checks of a like amount without adjusting the printing elements 80 after each printing operation. This is especially desirable where a large number of 85 checks for a like amount are to be issued, as in paying off a large group of workmen getting the same wage. The resetting device when in operative position as shown in Fig. 12, will cooperate with the projections 36 90 and permit the springs 35 to return the printing elements to normal printing positions, this being effected immediately after the printing has been completed by the 95 printing element. The proper alignment of the characters is insured through the aligning device 49 which cooperates with the projections 46 to effect proper engagement between the shoulders 34 and the plate 41. Excessive spacing between the characters in 100 the printing matter is avoided by returning the work slightly after each printing operation through the spring device 54 which acts on the slip-off device cooperating with the shaft on which the rupturing device 46 105 is mounted, engagement of the work with the rupturing device being sufficient to effect this return.

From the foregoing it will be seen that there has been provided a printing machine 110 in which the printing elements are arranged on a rotary carrier in such a manner that they may be moved radially with reference to the turning axis of the carrier to printing position on such carrier. This radial movement is effected through a simple means which provides a firm support for the printing elements during the printing action. A simple means is also provided for locking the printing elements in printing position. 115 The printing elements are automatically released from the locking means after the printing operation and the releasing or resetting means is movable to an inoperative position so that a repetition of the printing operation may take place with the same character or characters. Means is also provided which insures the proper aligning of the printing characters, and a means is employed which automatically shifts the work 120 125 130

in a direction opposite to the feeding direction, so that a proper spacing between the characters on the printing matter may be obtained. This return movement of the work is accomplished through a spring means which has a slip connection with the rupturing means below the work so that the rupturing means may complete its rupturing action and will, when freed by the rupturing means on the printing element, return a slight distance under the action of the spring to produce a slight return movement of the work.

What I claim as my invention and desire 15 to secure by Letters Patent is:—

1. A printing machine comprising a platen, a rotary carrier, and a plurality of printing elements mounted on said carrier and movable radially and axially of the carrier 20 to and from a printing position for cooperation with the platen.

2. A printing machine comprising a rotary platen, a rotary carrier, a plurality of printing elements mounted on the carrier 25 and adapted to cooperate with the platen on the rotation of the carrier, and cooperating surfaces on the printing elements and the carrier for effecting a movement of the printing elements to printing positions on 30 the carrier when pressure is applied to said printing elements in a line transversely of the plane of movement of the carrier.

3. A printing machine comprising a platen, a rotary carrier, printing elements mounted 35 on the carrier, and cooperating surfaces on the printing elements and the carrier for effecting the movement of the printing elements radially of the carrier to a printing position when pressure is applied to the 40 printing elements in the direction of the axis of turning of the carrier.

4. A printing machine comprising a platen, a rotary carrier, and a plurality of printing elements movable axially and radially of 45 said carrier and each provided with a key at one end.

5. A printing machine comprising a rotary platen, a rotatable carrier, a plurality of printing elements movable on the carrier 50 to and from a position for cooperation with the platen on the rotation of the carrier, and means for automatically effecting the resetting of said printing elements to normal printing position on the rotation of the carrier and after the printing elements have 55 co-operated with the platen.

6. A printing machine comprising a rotary platen, a rotary carrier, a plurality of printing elements movable on the carrier to 60 and from printing position on the rotation of the carrier, locking means for securing the printing elements in printing position on the carrier, springs for returning said printing elements to non-printing position, 65 and means for effecting the release of said

printing elements from the locking means on the rotation of the carrier after the cooperation of the printing elements with the platen.

7. A printing machine comprising a rotary platen, a rotary carrier, printing elements mounted on the carrier and movable thereon to and from printing positions for 70 cooperating with the platen on the rotation of the carrier, locking means for locking the printing elements in printing position on 75 the carrier, and means for effecting the unlocking of the printing elements to permit them to move to non-printing position on the carrier on the rotation of the carrier after the cooperation of the printing elements with the platen.

8. A printing machine comprising a rotary platen, a movable carrier, printing elements mounted on the carrier and movable thereon to and from printing positions for 80 cooperating with the platen on the rotation of the carrier, locking means for locking the printing elements in printing position on the carrier, and means for effecting the unlocking of the printing elements to permit them 85 to move to non-printing position on the carrier on the rotation of the carrier after the cooperation of the printing elements with the rotary platen, said unlocking means being movable toward and from operative position.

9. A printing machine comprising a rotary platen, a rotary carrier, printing elements movably mounted on the carrier to move to and from printing position for 100 cooperation with the platen on the rotation of the carrier, and means for effecting the automatic return of the printing elements to non-printing position after the cooperation of the elements with the platen on the rotation of the carrier after the cooperation of 105 the printing elements with the rotary platen, said means being movable to an inoperative position.

10. A printing machine comprising a platen, a rotary carrier, a plurality of printing elements mounted on said carrier and movable radially and axially of the carrier to and from a printing position for cooperation with the platen, and means for effecting 110 the automatic return of the printing elements to non-printing position after cooperation of the elements with the platen.

11. A printing machine comprising a platen, a rotary carrier, a plurality of printing elements mounted on said carrier and movable radially and axially of the carrier to and from a printing position for cooperation with the platen, and means for effecting 115 the automatic return of the printing elements to non-printing position after cooperation of the elements with the platen, said means being movable to an inoperative position.

12. A printing machine comprising a 120

platen, a rotary carrier, a plurality of printing elements mounted on the carrier and movable radially and axially of the carrier to and from a printing position for cooperation with the platen, locking means for locking said printing elements in printing position on the carrier, and means for effecting the unlocking of the printing elements to permit them to move to non-printing position on the carrier.

13. A printing machine comprising a platen, a rotary carrier, printing elements mounted on the carrier, cooperating surfaces on the printing elements and the carrier for effecting movement of the printing elements radially of the carrier to printing positions when pressure is applied to the printing elements in the direction of the axis of turning of the carrier, a locking shoulder on each printing element, an inclined surface on each printing element leading to said locking shoulder, means on the carrier for cooperating with said inclined surface to engage behind the shoulder, and spring means for acting on the printing elements to maintain the shoulder against said means on the rotary carrier and also to return the printing element to non-printing position when the shoulders disengage with said means on the carrier.

14. A printing machine comprising a platen, a rotary carrier, printing elements mounted on the carrier, cooperating surfaces on the printing elements and the carrier for effecting movement of the printing elements radially of the carrier to printing positions when pressure is applied to the printing elements in the direction of the axis of turning of the carrier, a locking shoulder on each printing element, an inclined surface on each printing element leading to said locking shoulder, means on the carrier for cooperating with said inclined surface to engage behind the shoulder, spring means for acting on the printing elements to maintain the shoulder against said means on the rotary carrier and also to return the printing element to non-printing position when the shoulders disengage with said means on the carrier, and means for cooperating with said printing elements for causing the shoulders to become disengaged with the means on the carrier in order that they may be returned to non-printing position by the springs.

15. A printing machine comprising a platen, a rotary carrier, printing elements mounted on the carrier, cooperating surfaces on the printing elements and the carrier for effecting movement of the printing elements radially of the carrier to printing positions when pressure is applied to the printing elements in the direction of the axis of turning of the carrier, a locking

shoulder on each printing element, an inclined surface on each printing element leading to said locking shoulder, means on the carrier for cooperating with said inclined surface to engage behind the shoulder, spring means for acting on the printing elements to maintain the shoulder against said means on the rotary carrier and also to return the printing element to non-printing position when the shoulders disengage with said means on the carrier, and means for cooperating with said printing elements for causing the shoulders to become disengaged with the means on the carrier in order that they may be returned to non-printing position by the springs, said means being movable to a non-operative position.

16. A printing machine comprising a platen, a rotary carrier, a plurality of printing elements mounted on the carrier, cooperating surfaces on the printing elements and the carrier for effecting the movement of the printing elements radially of the carrier to printing positions when pressure is applied to the printing elements in the direction of the axis of turning of the carrier, cooperating means on the carrier and the printing elements for effecting the locking of the printing elements in printing position, springs for maintaining the cooperating locking devices in cooperation and acting also to return the printing elements to non-printing positions, and means for cooperating with said printing elements to effect the disconnection of the cooperating locking devices in order that the springs may return the printing elements to non-printing positions.

17. A printing machine comprising a platen, a rotary carrier having radial grooves with bottoms inclined to the axis of turning of the carrier, printing elements arranged in said grooves and having surfaces cooperating with the inclined bottom walls, and keys connected with said printing elements to permit the latter to be moved in the direction of the axis of rotation of said carrier by cooperation with the inclined bottom walls of the groove.

18. A printing machine comprising a platen, a rotary carrier having surfaces inclined to the axis of turning of said carrier, and printing elements cooperating with said surfaces to move in the direction of the axis of turning of the carrier and also radially of the carrier to printing positions on the carrier for cooperation with the platen.

19. A printing machine comprising a platen, a rotary carrier having surfaces inclined to the axis of turning of said carrier, and printing elements cooperating with said surfaces to move in the direction of the axis of turning of the carrier and also radially of the carrier to printing positions

on the carrier for cooperation with the platen, and means for locking the printing elements in printing positions on the carrier.

5 20. A printing machine comprising a platen, a rotary carrier, printing elements movable on the carrier radially and also in the direction of the axis of the carrier, each of said printing elements being provided 10 with an inclined surface and with a shoulder, and holding means on the carrier for cooperation with said surface to cause said means to engage behind the shoulder in order to lock the printing element in printing 15 position on the carrier.

21. A printing machine comprising a platen, a rotary carrier, printing elements movable on the carrier radially and also in the direction of the axis of the carrier, each 20 of said printing elements being provided with an inclined surface and with a shoulder, holding means on the carrier for cooperation with said surface to cause said means to engage behind the shoulder in 25 order to lock the printing element in printing position on the carrier, and an aligning device for cooperating with said printing elements to cause said shoulders to firmly engage with said means, said aligning device 30 being positioned to operate on the printing elements immediately before the latter cooperate with the platen.

22. A printing machine comprising a platen, a rotary carrier, printing elements 35 movable on the carrier radially and also in the direction of the axis of the carrier, each of said printing elements being provided with an inclined surface and a shoulder, holding means on the carrier for cooperation 40 with said surface to cause said means to engage behind the shoulder in order to lock each printing element in printing position on the carrier, springs acting on said printing elements to hold the shoulders in engagement 45 with said means, and means for cooperating with the printing elements for moving the shoulders on the printing elements out of engagement with the holding means on the carrier to permit the return 50 of the printing elements to non-printing position.

23. A printing machine comprising a platen, a rotary carrier, printing elements 55 movable on the carrier radially and also in the direction of the axis of the carrier, each of said printing elements being provided with an inclined surface, a shoulder and a projection at one side of the carrier, holding means on the carrier for engaging 60 said inclined surface and the shoulder of each printing element, springs secured to said elements and to the carrier and acting to hold the shoulders in cooperation with the holding means on the carrier, said springs 65 also acting to return the printing elements to

nonprinting positions when the shoulders are disengaged from said holding means, and means cooperating with said projections to move the printing elements so that the shoulders are disengaged from said holding 70 means in order to be returned to non-printing positions under the actions of the springs.

24. A printing machine comprising a platen, a rotary carrier having radial 75 grooves with surfaces inclined to the axis of turning of said carrier, printing elements cooperating with said surfaces to move in the direction of the axis of turning of the carrier and also radially of the carrier to print- 80 ing positions on the carrier for cooperating with the platen, said printing elements each having an inclined surface, a shoulder, and a projection beyond one side of the carrier, holding means on the carrier for cooperation 85 with the surfaces on the printing elements to cause said shoulders to engage with said means, springs acting on said printing elements to hold the shoulders in cooperation with said holding means to return the print- 90 ing elements to non-printing positions, and means arranged to cooperate with said projections for the purpose of moving the printing elements in order that their shoulders may be disengaged from the holding means 95 on the carrier so that the printing elements may be returned to non-printing positions under the action of the springs.

25. A printing machine comprising a platen, a rotary carrier, printing elements 100 movable on the carrier and also in the direction of the axis of the carrier, means for locking said printing elements in printing positions on the carrier, and means for effecting the return of the printing elements 105 to non-printing position embodying a roller cooperating with portions of the printing elements and movable axially to a position where it will be inoperative.

26. A printing machine comprising a 110 rotary platen, a rotary rupturing device mounted to turn about an axis common to the axis of turning of the platen, a rotary carrier, printing surfaces mounted on the carrier to cooperate with the rotary platen, 115 and rupturing means mounted on said carrier to cooperate with the rotary rupturing device.

27. A printing machine comprising a 120 movable carrier, printing surfaces mounted on said carrier, rupturing means mounted on said carrier to move with the latter, a platen for cooperating with the printing surfaces, and a rupturing device for cooperating with the rupturing means on the carrier.

28. A printing machine comprising a rotary carrier, printing surfaces mounted on said carrier, rupturing means mounted on said carrier, a rotary platen for cooperating 125 with the printing surfaces, and rupturing 130

means for cooperating with the rupturing means on the carrier.

29. A printing machine comprising a rotary platen, a rotary rupturing device 5 mounted to turn about an axis common to the axis of turning of the platen, a rotary carrier, and printing elements movably mounted on the rotary carrier, each of said printing elements having a printing surface 10 for cooperation with the platen and a rupturing surface for cooperating with the rotary rupturing device.

30. A printing machine comprising a platen and a printing element mounted to 15 move together to print and simultaneously feed the work, and means for returning the work slightly after a printing operation in order to obtain proper spacing between the different printing operations of the machine.

31. A printing machine comprising a rotary platen, a rotatably mounted printing element cooperating with the platen to print and to feed the work, means for moving the work between the different printing operations 25 in the opposite direction to that which it is fed by the platen and the printing element.

32. A printing machine comprising a platen and a printing element movable together to print and to feed the work, rupturing means operating during such printing and feeding of the work, means cooperating with said rupturing means for effecting the slight return of the work between the 35 different printing and feeding operations.

33. A printing machine comprising a rotary platen, a rupturing roller mounted to turn about an axis common to the axis of turning of the platen, a rotary carrier, printing surfaces mounted on the carrier for cooperation with the platen, rupturing surfaces mounted on the carrier for cooperating with the rupturing roller, and means for 40 cooperating with the rupturing roller to return the work slightly between the different printing operations.

34. A printing machine comprising a rotary platen, a rotary rupturing roller mounted to turn about an axis common to the axis 50 of turning of the platen, a rotary carrier, a printing surface mounted on the carrier to turn therewith to cooperate with the platen, rupturing surfaces mounted on the carrier to turn therewith to cooperate with the rotary rupturing roller, and means in which energy is stored during the rupturing operation to return the rupturing roller a slight distance in order to feed the work backwardly.

35. A printing machine comprising a rotary platen, a rotary rupturing roller mounted to turn about an axis common to the axis of turning of the platen, a rotary carrier, a printing surface mounted on the 65 carrier to turn therewith in order to cooper-

ate with the platen, rupturing surfaces mounted on the carrier to turn therewith to cooperate with the rotary rupturing roller, and spring means having a slip connection with the rupturing roller and adapted to have energy stored therein during the rupturing movement for the purpose of moving the rupturing roller a slight distance backwardly.

36. A printing machine comprising a 75 printing element, a rupturing roller turning to rupture the work during the printing, and means for operating said rupturing roller in the opposite direction from that which it moves during the printing in order 80 to return the work a slight distance for the next printing action.

37. A printing machine comprising a printing element, a rupturing roller moved in one direction during the printing to 85 rupture the work, and means for automatically operating said rupturing roller in the opposite direction after each printing action to feed the work a slight distance 90 backwardly.

38. A printing machine comprising a printing element, a rupturing roller movable in one direction during the printing to rupture the work operated upon by said printing elements, and spring means in which energy 95 is stored during the rotation of the rupturing roller on the printing operation for moving said rupturing roller a slight distance in the opposite direction after the printing operation. 100

39. A printing machine comprising a printing element, a rupturing roller moved in one direction to rupture the work operated upon by said printing element, and a spring having a slip connection with the rupturing roller and arranged to have energy stored therein when the rupturing roller moves during the printing operation for the purpose of moving said rupturing roller a slight distance in the opposite direction after 110 the printing operation.

40. A printing machine comprising a printing element, a rupturing roller cooperating with the work operated upon by said printing element and moved in one direction 115 during a printing operation, a cylindrical part turning with said rupturing roller, a device having a slip connection with said cylindrical part and having its movement limited, and a spring connected with said device and having energy stored therein when the rupturing roller is moved during the printing, said spring returning the rupturing roller a slight distance through the medium of said device after the printing 120 operation is discontinued for the purpose of returning the work a short distance.

41. A printing machine comprising a rotary platen, a rotary rupturing device, a shaft on which both of said devices are 130

mounted, a rotatably mounted printing element for cooperation with the platen to print and feed the work, means moving with said printing element for cooperation with the rupturing device, a cylindrical part on the shaft of the platen and the rupturing roller, a device having a slip connection with the cylindrical device on said shaft and having

its movement limited in two directions, and a spring connected with said device and having energy stored therein during the movement of the rupturing roller on the printing movement for the purpose of returning the work a slight distance after such printing movement.

JOHN HEBERLING.
